UNITED STATES PATENT OFFICE.

THOMAS J. BUSH, OF LEXINGTON, KENTUCKY.

BORING-GAGE.

SPECIFICATION forming part of Letters Patent No. 293,144, dated February 5, 1884.

Application filed May 3, 1883. (No model.)

To all whom it may concern:

Be it known that I, THOMAS J. BUSH, of Lexington, in the county of Fayette and State of Kentucky, have invented a new and Improved Boring-Gage, of which the following is a full, clear, and exact description.

This invention relates to my patent for "boring-gage," dated May 2, 1882, and numbered 257,288, and also to my two patents for "locking and interlocking bolts," dated, respectively, May 2, 1882, (No. 257,288,) and September 19, 1882, (No. 264,622;) and my present invention consists in adapting the gage to be held, and of the means for holding the gage, upon a railroad-tie parallel with the rail, so that the intersecting diagonal holes for receiving the bent bolts may be bored in the tie at the side of the rail instead of crossing under it, as described in my above-mentioned patents.

Reference is to be had to the accompanying drawings, forming part of this specification, in which similar letters of reference indicate corresponding parts in all the figures.

Figure 1 is a broken side elevation of the boring-gage as it appears when locked in position for use. Fig. 2 is a cross-sectional elevation of the same, taken on the line *x* *x* of Fig. 1, showing the preferred form of device for locking the gage to the rail; and Fig. 3 is a sectional elevation, showing a modified form of the locking device.

The boring-gage A, instead of being adapted to straddle the railroad-rail B, and to be secured to it for use by means of hinged jaws operated by screws, as in my former patent, is made somewhat lower than the rail, so that it may be placed upon the tie C, alongside of the rail B, and held there for use by the locking device D, attached to the rail, the holding-screw *d* of the device resting upon the central seat, *a*, of the gage, as shown in the drawings,

The locking device D consists, by preference, of the cramp-iron *f*, carrying the said screw *d*, and also the screw *g*, which latter is held at right angles to the screw *d*, and when in use reaches under the head of the rail and comes against the web of the rail, as shown clearly in Fig. 2, so that the projection *f'* of the iron *f*, which reaches slightly under the head of the rail, will grasp the rail when the

screw *d* is turned, and thus hold the screw *d* to its work, as will be understood from Fig. 2.

In the form of locking device shown in Fig. 3, the screw *g* and arm *f''* are dispensed with, and the projection *f'* replaced by a projection, *f''*, having an elongation to form a jaw that is adapted to catch under the head of the rail, and thus hold the screw *d* to its work. This latter device is not adapted to rails of different sizes, but the locking device shown in Figs. 1 and 2 is, since the screw *g* and projection *f'* act in conjunction for securing the device to the rail, and the screw *g* may be adjusted to suit any size of rail, whether large or small.

Constructed in this manner it will be seen that the gage is adapted to be held upon the tie C for boring diagonal intersecting holes, so that the rails may be held upon the ties by means of the plates F and my interlocking bolts; and the plates F are inclined or bevelled at their ends, so that the nuts of the bolts will fit properly upon them, as will be clearly understood from Fig. 2.

Having thus described my invention, what I claim as new, and desire to secure by Letters Patent, is—

1. The boring-gage A, having the seat or similar rest *a*, in combination with means, substantially as described, for locking the gage to and parallel with the rail, as and for the purposes set forth.

2. The locking device D, having a forked end adapted to bear against the top, against one side, and against the under side of the head or tread of the rail, in combination with the boring-gage A, substantially as and for the purpose set forth.

3. The cramp-iron *f*, carrying screw *d*, and formed with the projection *f'*, adapted to catch against or under the head of the rail B, in combination with the boring-gage A, substantially as and for the purposes set forth.

4. The cramp-iron *f*, formed with the projection *f'* and arm *f''*, and provided with the screws *d* *g*, in combination with the boring-gage A, substantially as and for the purposes set forth.

THOMAS J. BUSH.
